REMOTELY CONTROLLED RADIORECEIVER

Carl E. Johnson, Los Angeles, Calif.

Application December 11, 1926
Serial No. 154,147

9 Claims. (Cl. 250—40)

This invention relates to radio receiving sets and particularly to a remote control radio receiving set which is especially valuable in large residences, hospitals, or other institutions where it is advantageous to have complete control of the operation of a radio set from a point at some distance from the set itself.

It is common practice to install a central radio set in such buildings and run wires to remote loud speaker locations so that radio programs may be enjoyed in various parts of the building. By this method it is impossible to control the radio set itself from the remote loud speaker station.

15 It is an object of my invention to provide a radio set which can be completely controlled from a remote station.

A further object is to provide a remotely controlled radio set in which the tuning is accomplished by operating an electric motor.

It is a further object of my invention to provide a remotely controlled radio set in which the radio broadcasting station to which the set is tuned is indicated at a remote control station.

25 A still further object is to provide a radio set installation in which programs may be enjoyed simultaneously in different locations of a building from a central station.

Further objects and advantages of my invention will be made evident in the following description.

Referring to the drawings in which I illustrate a preferred form of my invention,

Fig. 1 is a schematic wiring diagram.
35 Fig. 2 is a front view of the controller.
Fig. 3 is a side view of the controller.

Fig. 4 is a fragmentary view showing the means of mounting the motor in relation to the tuning element.

40 Fig. 5 is a partially sectioned view taken substantially on the line 5—5 of Fig. 4.

Fig. 6 is a detailed front view showing the adjustable contactors.

Fig. 7 is a detailed side view of one of the contactors.

Referring in detail to the drawings, Fig. 1 shows a radio receiving set 10 adapted to be controlled by a portable controller 11 from one of a number of remote control stations. In Fig. 1 two of these remote control stations 12 and 13 are shown diagrammatically, each consisting of a wall receptacle 14 into which a multi-circuit plug 15 may be plugged. This plug is connected to the portable controller 11 by a cable 16.

55 As best shown in Figs. 1, 4 and 5, the radio set

10 contains a tuning device in the form of a variable condenser 21 having plates 22, but any other type may be provided if desired. The condenser 21 is mounted on a panel 23 of the radio set 10 by means of supports 24. A shaft 25 of the condenser 21 extends through an opening 26 of the panel 23 and has a tuning dial 27 mounted rigidly thereon for hand operation of the tuning device. A metal spiral gear plate 28 is also mounted on the shaft 25 and held rigidly in place by a set screw 29.

Adapted to mesh with the gear plate 28 is a worm gear 30 mounted on a shaft 31 of a motor 32. The motor 32 is preferably of the slow speed, direct current type having an armature 33 and a field winding 34, as indicated diagrammatically in Fig. 1. A pin 37 is mounted in the panel 23 and rotatably supports the motor 32 as shown in Fig. 4. Extending downward from the left end of the motor 32 is a follower 38 which is adapted to be engaged by a cam 39 pivoted to the panel 23 at 40. An arm 41 of the cam 39 extends through an arcuate opening 42 of the panel 23. The cam 39 is so designed that when the arm 41 rests in the lower part of the arcuate opening 42 the follower 38 engages the cam 39 in such a way as to hold the motor 32 in the position shown in full lines, thus meshing the worm gear 30 with the gear plate 28. When the arm 41 rests in the upper part of the opening 42 in the position shown by dotted lines 43, the cam 39 allows the follower 38 to drop into its dotted line position, thus causing the motor 32 to pivot about the pin 37, and consequently disengaging the worm gear 30 and the gear plate 28. This disengaged position of the worm 30 is indicated by dotted lines 44, and when in this position allows the tuning device to be freely rotated by means of the dial 27 so that it is possible to operate the radio set 10 by hand.

The motor 32 is adapted to be operated by a motor control switch 50 mounted in the portable controller 11. The mechanism of the switch is shown diagrammatically as comprising an insulating support 54 which is attached to a shaft 52 which extends through a front plate 53 of the portable controller 11, and which supports radial metallic arms 55 and 56. The arm 55 acts as a contact arm for forward variable resistance 58 when the shaft 52 is rotated in a clockwise direction, this being accomplished by operating a knob 51 which is secured to the shaft 52. The right end of the forward resistance 58 is connected by a wire 59 to the left side of the armature 33 of the motor 32. When the 1

knob 51 is rotated in a counter-clockwise direction the arm 55 acts as a contact arm for reverse variable resistance 60, the left end of which is attached to the right side of the armature 33 by a wire 61. Compression springs 62 engage the arm 55 and are adjusted to always return the switch 50 to its off position shown in Fig. 1 when the knob 51 is released.

Simultaneously with the arm 55 contacting the forward resistance 58 when the knob 51 is rotated in a clockwise direction, the arm 56 engages an auxiliary contact 63 and a field contact 64. The auxiliary contact 63 is connected to the left end of reverse resistance 60 by a wire 63^a. The field contact 64 is attached to one terminal of the motor field 34 by a wire 66. When the knob 51 is rotated counter-clockwise, the arm 56 engages an auxiliary contact 68 and a field contact 69. The auxiliary contact 68 is connected to the right end of the forward resistance 58 by a wire 68^a. The field contact 69 is connected to the field contact 64 by a wire 70. The arm 55 is connected to a wire 72 through a flexible lead. The wire 72 is joined by wires 73 and 74 to the positive side of a storage battery 75. The arm 56, on the other hand, is connected to the negative side of the battery 75 through a flexible lead, wires 76, 77 and 78, contact elements 79 and 80 of a magnetic switch 82 and wire 83. A wire 83^a connects the upper terminal of the field 34 to the wire 73.

The motor control switch 50 offers a means of starting, stopping, reversing, and varying the speed of the motor 32 of the radio set 10, thus controlling the movement and position of the tuning device. When turned clockwise the switch 50 sends current through the armature 33 in an opposite direction than when turned counter-clockwise, but does not vary the direction of the current flowing through the field 34 of the motor 32. This causes the motor 32 to rotate in opposite directions with the rotating of the knob 51 clockwise and counter-clockwise. The angular displacement of the knob 51 determines the position of the arm 55 on the forward or reverse resistances 58 and 60, which in turn varies the amount of resistance in the armature circuit of the motor 32. Thus when the arm 55 first makes contact with one of the resistances a maximum resistance is placed in series with the armature 33, thus causing the motor 32 to rotate very slowly. Further movement of the knob 51 cuts out resistance, thus increasing the speed of the motor 32, the maximum speed being attained when the resistance is cut completely out of the circuit by the arm 55 making direct contact with either the wire 59 or the wire 61, depending on whether the motor 32 is running forward or backward.

The magnetic switch 82 is operated by the energizing of one of two oppositely disposed solenoids 84 and 85. This is accomplished remotely by means of an operating switch 86 mounted in the portable controller 11 and actuated by a knob 87 pivoted on the face thereof. The knob 87 rotatably supports a contact arm 88 which is connected to the negative side of the battery 75 by a wire 89. When the arm 88 is rotated clockwise, it engages a contact point 90 which is connected to the upper terminal of the solenoid 84 of the magnetic switch 82 by a wire 91. Rotating the arm 88 in a counter-clockwise direction allows it to engage a contact point 92 which is connected to the lower terminal of the solenoid 85 by a wire 93. The lower terminal of the solenoid 84 and the

upper terminal of the solenoid 85 are joined by a wire 95, to which a wire 96 is attached which leads to the positive side of the battery 75. Rotating the knob 87 clockwise therefore energizes the solenoid 84, while counter-clockwise rotation energizes the solenoid 85. The arm 88 is always brought to the off position shown in Fig. 1 by means of a tension spring 97 attached thereto.

Operating in the magnetic fields of the solenoids 84 and 85 is an armature 100 pivoted about a point 101 and so placed that the right end of the armature 100 is acted upon by the energizing of either of the solenoids 84 or 85. The left end of the armature 100 is adapted to engage the contact element 80 of a compound jack 103 when the armature 100 is in the dotted line or "on" position indicated at 104. The jack 103 comprises contact elements 79 and 80, mentioned previously, and contact elements 106 and 107, all mounted in an insulation block 108. When the solenoid 84 is energized the armature 100 is drawn into its dotted line position 104. This causes the left end of the armature 100 to engage the contact element 80, moving it to the left into its dotted line position, at which time it is in contact with the contact element 79. An insulating strip 109 transmits this motion from the contact element 80 to the contact element 106 and causes the latter to engage the contact element 107.

It should be understood that any number of contact elements may be placed in the jack 103, depending on the number of circuits to be controlled by the magnetic switch 82, in turning the radio set 10 on and off, which in turn will depend on the type of radio set being used. I have shown a pair of power amplifier input terminals 110 and 111 mounted on the panel 23 of the radio set 10. A wire 112 connects the terminal 111 and the contact element 107. The terminal 110 and the contact element 106 are shown connected to a source 113 of alternating current power by wires 113 and 114 respectively. Thus, when the armature 100 is in the dotted line position 104, the contact elements 106 and 107 will be in engagement and will supply the alternating voltage required for this type of power amplifier to the power amplifier input terminals 110 and 111.

Filament current is supplied to the radio set 10 through terminals 120 and 121 which are connected respectively to the wires 73 and 77. A wire 122 connects the terminal 120 and the shaft 25 of the tuning condenser 21. The operation of the magnetic switch 82 supplies the radio set 10 with filament or "A" current from the battery 75. Plate or "B" current is furnished through conventional "B" batteries, not shown.

Mounted on the supports 24 of the variable condenser 21 is a contact plate 130 made of insulating material in which a compound, semi-circular groove 131 is cut, this groove 131 supporting a number of adjustable contactors 134 as best shown in Figs. 5, 6 and 7. The contactors 134 have body members 135 with legs 136 and 137 extending in parallel directions from diagonally opposite corners of the body members 135. The leg 136 is adapted to fit in the compound groove 131 while the leg 137 lies flat against a face 139 of the contact plate 130, the contactor being held in position by a spring 140 which engages one face of the compound groove 131. These contactors are easily inserted in the groove 131 of the contact plate 130, and once inserted can be moved in the semi-circular path offered by the groove. A brush 141 is mounted on the gear plate 28 in such a position as to successively contact the legs 137 of the

contactors 134 when the gear plate 28 is rotated, wires 195 and 196 respectively. Throughout Fig. 1 the loud speaker leads are shown in heavy lines in the contact plate 130 and are numbered from for the sake of clearness in checking out the 144 to 149 inclusive. Connected to the contactors circuits. A variable resistance 198 is shown mounted 5 in the base of the loud speaker 191 and connected across the terminals thereof for the purpose of regulating the volume of sound produced. Because all the remote control stations are 10 144 to 149 inclusive, through flexible leads, are 80 wired in parallel in all respects, it should be clear 150 to 155 inclusive which are connected to one terminal of their respective signal lights 160 to 165 inclusive which are mounted on the face of the portable controller 11 in a circular arrangement. Thus, the contactor 144 is connected to the signal light 160 through the wire 150; the contactor 145 to the signal light 161 through the wire 151, etc. The remaining terminals of each 10 15 of the signal lamps 160 to 165 inclusive are connected together by means of a wire 167 which is joined to the wire 77. The signal lights 160 to 165 inclusive are for the purpose of indicating the position of the variable condenser 21 to the operator stationed at the portable controller 11. They are so wired that any one of the signal 20 lights will be lit when its respective contactor is engaged by the brush 141, provided that the magnetic switch 82 is in its "on" position as shown by the dotted lines 104. Thus when the brush 141 engages the contactor 144, the signal light 160 will light. The contactors 144 to 149 inclusive may conveniently be adjusted in the groove 131 so that they light their respective 25 signal lights when different broad-casting stations are tuned in. Thus in Fig. 2 these signal lights are shown accompanied by the call letters of their respective stations. The signal light burning always indicates to the operator at the remote control station the station tuned in and also the relative position of the variable condenser plates 22.

A pilot lamp 170 is mounted to the left of the knob 87 of the portable controller 11 for the purpose of indicating the position of the magnetic switch 82. The wires 77 and 73 terminate at the terminals of the pilot lamp 170 and conduct current from the battery 75 when the magnetic switch 82 is in the "on" position.

The multi-circuit plug 15, to which the portable controller 11 is connected by the cable 16, is adapted to fit any of the wall receptacles 14 of the remote control stations 12 and 13. The multi-circuit plug 15 is composed of a plurality of pins 175 which are adapted to snugly engage female members 176 of the wall receptacle 14 when the plug 15 is inserted therein. Each of the wires in the cable 16 is connected to one of the pins 175 and each female member 176 is connected to a wire leading to the location of the radio set 10. Mounted in the center of the multi-circuit plug 15 is a conventional loud speaker plug 177 consisting of a shank 178 and a tip 179 which are adapted to engage a shank contact 180 and a tip contact 181 of a jack 183 mounted in the center of each of the wall receptacles 14. The tip 179 and shank 178 are shown connected by leads 185 and 186 to a loud speaker jack 190 mounted on the face 53 of the portable controller 11. A loud speaker 191 is connected to the loud speaker jack 190 through a plug (not shown) which is identical in construction and size with the loud speaker plug 177 mounted in the center of the multi-circuit plug 15. Thus a loud speaker with its conventional plug may be plugged into the jack 190 mounted on the portable controller 11, or it may be plugged directly into any of the wall receptacles 14 where it will contact the tip contact 181 and the shank contact 180. These tip and shank contacts 181 and 180 are shown connected to output terminals 193 and 194 of the radio set 10 through

wires 195 and 196 respectively. Throughout Fig. 1 the loud speaker leads are shown in heavy lines for the sake of clearness in checking out the circuits. A variable resistance 198 is shown mounted in the base of the loud speaker 191 and connected across the terminals thereof for the purpose of regulating the volume of sound produced. Because all the remote control stations are 80 wired in parallel in all respects, it should be clear 85 that when the radio set 10 is being controlled from one remote control station, i. e., the station 13 for instance, the same program may be enjoyed at other remote control stations, such as 12, by inserting the plug of a loud speaker in the jack 181 of the wall receptacle 14 situated at the 90 remote control station 12. This connects the loud speakers at the stations 12 and 13 in parallel and the volume may be diminished by adjusting the variable resistance 198 and thus shunting a portion of the loud speaker energizing current 95 through this resistance.

In thus operating a motor in the vicinity of a radio set a click is sometimes experienced when the motor controlling switch 50 is first rotated, due to the motor field acting on the wires inside 100 the radio set and inducing a slight potential therein. I have found that all trouble from this source can be eliminated by shielding the motor 32 with a metal shield and shunting both the armature terminals and the field terminals with 105 a fixed resistance of about 200 ohms. In Fig. 1 a resistance 200 is shown shunted across the terminals of the armature 33 and a resistance 201 is shown shunted across the terminals of the field 34.

The operation of my invention is substantially 110 as follows.

The portable controller 11 is carried to any desired remote control station and is placed at any convenient location in the room within reach 115 of the wall receptacle 14 through the cable 16. The multi-circuit plug 15 is inserted in the wall receptacle 14, thus connecting the wires in the cable 16 to corresponding wires leading to the radio set 10. The loud speaker 191 is plugged 120 into the jack 190 of the portable controller 11.

The operating switch 86 is momentarily moved in a clockwise direction, thus making contact between the arm 88 and the contact point 90. With the switch in this position, current flows 125 from the positive side of the battery 75, through the wires 96 and 95, through the solenoid 84, and the wire 91 to the contact point 90, whence it is conducted through the arm 88 and the wire 89 to the negative side of the battery 75. This 130 current energizes the solenoid 84, causing it to attract the armature 100, moving it into the dotted line position shown at 104, where it remains until the solenoid 85 is energized. When the knob 87 of the operating switch 86 is released, the spring 97 returns it to its mid position, thus opening the circuit through the solenoid 84.

When the armature 100 is in the dotted line 135 position shown at 104, the contact elements 79 and 80 are in engagement as well as the contact elements 106 and 107. This completes a circuit from the positive side of the battery 75 through the wires 74 and 73 to the filament terminal 140 120, whence the current energizes the filaments of the vacuum tubes in the radio set 10, returning to the negative side of the battery 75 by means of the terminal 121, the wire 77, the wire 78, the contact elements 79 and 80, and the wire 83. Another circuit is completed from the 145

source of alternating current power through the wire 114, the contact elements 106 and 107, and the wire 112 to the power amplifier input terminal 111, whence it returns to the source of alternating current power through the terminal 110 and the wire 113.

Yet a further circuit is completed from the positive side of the battery 75 through the wire 74 and the wire 73 to the pilot lamp 170, whence it returns to the negative side of the battery 75 through the wires 77 and 78, the contact elements 79 and 80, and the wire 83. This lights the pilot lamp 170. Last of all, in the event that the brush 141 is contacting one of the contactors 134, for example, the contactor 144, current will flow from the positive side of the battery 75, through the wires 74, 73, and 122, through the shaft 25, the gear plate 28, the brush 141, the contactor 144, and the wire 150, to the signal light 160, whence it returns through the wires 167, 77, and 78, the contact elements 79 and 80, and the wire 83 which terminates at the negative terminal of the battery 75. This lights the signal light 160. Similar circuits can be traced if the brush 141 were touching any other contactor 134, in which case the corresponding signal light on the portable controller 11 would be lit.

In case the operator desires to tune the radio set to a different wave length he moves the motor controlling knob 51 either clockwise or counter-clockwise, depending on whether the wave length is to be raised or lowered. Turning the knob 51 clockwise completes a circuit from the positive terminal of the battery 75 through the wires 74, 73, and 72 to the arm 55 of the motor controlling switch 50. The arm 55 is at this time contacting the forward resistance 58 through which the current passes on its way to the armature 33 by way of the wire 59. Passing through the armature 33 the current is conducted through the wires 61 and 63^a to the auxiliary contact 63, whence it goes through the arm 56, wires 76, 77, 78, the contact elements 79 and 80, and the wire 83 to the negative terminal of the battery 75. Simultaneously a circuit is completed through the field 34 as follows. From the positive terminal of the battery 75 current flows through the wires 74, 73, 83^a, 50 through the field 34 of the motor 32, to the field contact 64 by means of the wire 66, whence it passes through the arm 56, the wires 76, 77, 78, the contact elements 79 and 80, and the wire 83 to the negative terminal of the battery 75. The armature and field of the motor 32 being now energized, the armature will turn, thus turning the variable condenser 21. As explained above, the speed of the motor 32 will be governed by the amount of rotation of the knob 51.

Turning the knob 51 in a counter-clockwise direction completes a circuit from the positive side of the battery 75, through the wires 74, 73 and 72, the arm 55, the reverse resistance 60, the wire 61, the armature 33, the wire 59, the wire 68^a, the auxiliary contact 68, the arm 56, the wires 76, 77, 78, the contact elements 79 and 80, and through the wire 83 to the negative side of the battery 75. It should be noted that the armature current has reversed in direction with the turning of the knob 51 in a counter-clockwise direction. The field current, however, does not reverse, traveling from the positive terminal of the battery 75, through the wires 74, 73 and 83^a, 70 through the field 34, the wire 66, the wire 70, the

field contact 69, the arm 56, the wires 76, 77, 78, the contact elements 79 and 80, reaching the negative terminal of the battery 75 through the wire 83. This reversal of the armature current and non-reversal of the field current reverse the motor 32.

The operator then holds the knob 51 in its turned position until the desired station is tuned in, which will be indicated by the lighting of the proper signal lamp. The knob 51 is immediately released, or if the variable condenser 21 has been turned a trifle too far the knob 51 may be momentarily reversed, thus reversing the motor 32 and turning the variable condenser back. Thus a very delicate adjustment can be effected. The volume of sound produced can be regulated either by shunting some of the loud-speaker current through the resistance 198 or by detuning the set; that is, by regulating the position of the variable condenser 21 so that it is a trifle to one side of the exact setting for loudest reception of the desired station.

In turning the set off, it is only necessary to momentarily rotate the knob 87 in a counter-clockwise direction and release it. This momentarily completes a circuit from the positive terminal of the battery 75, through the wires 96 and 95 to the solenoid 85, thence through the wire 93 to the contact point 88, where the current is conducted to the arm 86, returning to the negative terminal of the battery 75, through the wire 89. This current energizes the solenoid 85, thus pulling the armature 100 from its dotted line position 104 into its full line position which in turn opens the jack 103 and its attendant circuits 110 previously described.

It should be noted that turning the knob 51 before throwing the magnetic switch 82 by means of the knob 87 will have no effect on the motor insofar as the contact elements 79 and 80 are separated. Neither will any of the signal lamps be lighted unless the magnetic switch 82 is first closed.

In the event that it is desired to operate the radio set 10 from the set itself, all that is necessary is to move the arm 41 of the cam 39 into the position shown at 43 which disengages the worm gear 30 and the gear plate 28, thus allowing the condenser 21 to be turned by means of the dial 27. The control of the magnetic switch 82 is effected by manually moving the armature 100 into the desired position.

I claim as my invention:

1. In combination: a radio set having a tuning device; operating means for operating said tuning device; means situated at a remote point for actuating said operating means; an operating switch adapted to turn said radio set off and on; means at said remote point for controlling said operating switch; signal lights situated at said remote point; and means controlled by said tuning device for individually energizing said signal lights to indicate the particular station to which said radio set is tuned.

2. In combination: a radio set having a tuning element; a shaft in said tuning element; a gear plate mounted on said shaft; a reversible electric motor; gearing connecting said gear plate and said electric motor; means for disengaging said gearing; a series of remote control stations wired to said radio set; a controller at one of said remote control stations; means for operating said electric motor from said controller; signal lights on said controller indicating the position of said tuning element of said radio set; a magnetic

- switch adapted to turn said radio set on and off; means situated on said controller for operating said magnetic switch; a pilot lamp on said controller adapted to indicate the position of said 5 magnetic switch; and a loud speaker situated at any of said remote control stations. 80
3. In combination: a radio set having a tuning element; a shaft on said tuning element; a gear plate carried by said shaft; electrically-operated 10 means adapted to turn said shaft to adjust said tuning element; a remote control station; means at said station for controlling the operation of said electrically-operated means; a stationary plate, said plate having a groove concentric with 15 the axis of said shaft; contactors adjustably mounted in said groove; a brush contact carried by said gear plate, said brush contact making contact with said contactors as said tuning element is adjusted; and indicating means at said 20 remote control station for indicating which contactor said brush contact is engaging. 85
4. In combination: a radio set adapted to be tuned to the wave-length of a series of broadcasting stations; a remote control station; a plurality of signal lights at said remote control station for visibly indicating the broadcasting station to which said radio set is tuned, said signal lights being placed in the order of the wave-lengths of the stations they represent; and means 25 operatively connecting said radio set to said signal lights for energizing said lights to indicate the broadcasting station to which said radio set is tuned. 90
5. In combination: a radio set having a tuning element; a motor in said radio set adapted to actuate said tuning element; a controller wired to said radio set; a control switch on said controller, said control switch being adapted to operate said motor; an operating switch on said 30 controller; a magnetic switch adapted to turn said radio set on and off, said magnetic switch being operated by said operating switch; signal lights on said controller; and means interconnecting said tuning element and said signal 35 lights for individually illuminating said signal lights to indicate the station to which said radio set is tuned. 95
6. In combination: a radio set having a tuning element; a motor in said radio set adapted to 40 actuate said tuning element; a controller wired to said radio set; a control switch on said controller, said control switch being adapted to 45
- operate said motor; an operating switch on said controller; a magnetic switch adapted to turn said radio set on and off, said magnetic switch being operated by said operating switch; a pilot light on said controller, said pilot light being lighted when said magnetic switch is in an on position; and signal lights on said controller, said signal lights being adapted to indicate the station to which said radio set is tuned. 100
7. In combination: a radio set; a receptacle at a remote control station, said receptacle being wired to said radio set; a primary loud-speaker jack in said receptacle connected to the output of said radio set; a plug adapted to removably engage said receptacle; a controller electrically connected to said plug and adapted to control some element of said radio set; a secondary loud-speaker jack on said controller electrically connected to said primary loud-speaker jack when said plug engages said receptacle; a loud-speaker; and a plug on said loud-speaker and attachable to either said primary or said secondary loud-speaker jacks. 105
8. In combination: a radio set having a tuning element; a shaft on said tuning element adapted, when rotated, to tune said tuning element to stations of different wave-length; a brush contact adapted to rotate with said shaft; contactors adjustably mounted concentric with the axis of said shaft and adapted to be respectively contacted by said brush contact; and signal lights electrically connected to said contactors and said brush contact whereby the station to which said radio set is tuned is indicated by the lighting of the corresponding signal light. 110
9. In combination: a radio set providing a tuning element adapted when moved to successively tune in stations of different wave-length; a plurality of signal lights, each of said signal lights being associated with one of said stations; a circuit for each signal light; contact means for successively energizing the circuits of said signal lights when said tuning element is tuned whereby the operator may visibly know the station to which the set is tuned; and sound-reproducing means connected to said radio set and within hearing of said operator whereby said tuning element may be audibly tuned exactly to the wave-length of the station corresponding to the signal light which is lighted. 115
